UNITED STATES PATENT OFFICE.

ARTHUR Q. ADDISON AND WILLIAM E. HEALD, OF BALTIMORE, MARYLAND.

DESIGN FOR A PIN OR BADGE.

SPECIFICATION forming part of Design No. 25,935, dated August 18, 1896.

Application filed July 2, 1896. Serial No. 597,907. Term of patent 7 years.

To all whom it may concern:

Be it known that we, ARTHUR Q. ADDISON and WILLIAM E. HEALD, citizens of the United States, residing at Baltimore, in the State of Maryland, have invented and produced a new and original Design for Pins, Buttons, &c., of which the following is a specification, reference being had to the accompanying drawings.

10 Figure 1 is an elevation of our design on an enlarged scale. Fig. 2 is a horizontal central section of the same.

Our design comprises a shell-like form, having the outline of two heads of different persons joined back to back, and with the sides of the heads set at an angle to each other, as shown in Fig. 2. We preferably stamp our design from sheet metal; but it is obvious that it may be made of any suitable material.

20 We have shown the outline of the faces of McKinley and Hobart in dotted lines; but do not intend to limit ourselves to these, as we intend to use our design with the faces of any

other candidates or persons we may think desirable.

25 It is our intention to apply this design in the manufacture of pins, badges, lockets, buttons, &c., and do not intend to limit ourselves to any particular article or candidates, but shall use our design for any article or with 30 the "counterfeit presentment" of any person or persons we may deem suitable.

What we claim as new is—

The design for a pin, button, &c., comprising a shell-like form having the outline of two 35 heads joined back to back and with the sides of the heads arranged at an angle to each other, substantially as shown.

In testimony whereof we affix our signatures, in the presence of two witnesses, this 40 24th day of June, 1896.

ARTHUR Q. ADDISON.
WILLIAM E. HEALD.
